UNITED STATES PATENT OFFICE.

EPHRAIM DRENSHTEIN, OF BROOKLYN, NEW YORK.

ABDOMINAL SUPPORTING CORSET.

Application filed June 16, 1925. Serial No. 37,437.

This invention relates to corsets and supporters, and particularly to that type wherein an independent abdominal supporter is used in connection with a corset.

- 5 A combined abdominal supporter and corset which may be put on by the wearer as a unit and handled as a unit, but in which the supporter and the corset may be separately adjusted to give the wearer the greatest comfort while at the same time allowing the adjustment of the parts alternately so that the wearer may attain a figure of the best possible appearance, has long been sought.
- 10 My invention contemplates the adjustment of the supporter independently of whether the corset has been adjusted into operative position or not, the supporter being entirely unconnected to the corset and unconstrained thereby.

The various objects of my invention will be clear from the description which follows and from the drawings in which,

- 15 Fig. 1 is an outside view of my improved article of apparel as it appears when opened out substantially flat.

Fig. 2 is a perspective view of the abdominal supporter and of the corset assembled in the operative relation thereof, both partly adjusted into place.

20 Fig. 3 is a rear view of my device as it appears in operative position, and

Fig. 4 is a front view of the same.

In the practical embodiment of my invention I prefer to provide a corset 10, in which elastic members as 11 may be suitably arranged vertically throughout the entire height of the corset for automatically taking up any slight slack in the adjustment thereof to the body of the wearer, and in which the usual laces 12 at the center of the back are provided for accomplishing the major part of the adjustment. The usual cooperating hook and clasp members 13 and 14 are provided at the front center edges of the corset for securing said corset in position after the laces have been approximately adjusted to fit the wearer. In the rear sections 15 of the corset I provide openings as 16, into which the eyelets illustrated may be inserted, though it will be understood that a vertical slit of less extent than the height of the member 15 may be substituted for the eyelets shown. The connections 17 consisting preferably of the tapes shown are passed from the outside of the

corset to the inside thereof, through the eyelets or the slit as the case may be, and are 60 slideable horizontally therein. While said connections 17 are illustrated as tapes or laces, wide strips of any material suitable for this purpose may be used in place thereof, and I do not wish to be understood as limiting myself to the specific form of lacing or the specific form of opening illustrated herein for the purpose of providing 65 adjusting means for the supporter on the outside of the corset.

The supporter 18 comprises a pair of 70 similar separable sections 19 suitably securable together at the front center thereof as by means of the snap fasteners 20, the connecting members 17 being secured to the rear edge or to any other suitable point on said sections 19. Back or kidney supporting members 21 are secured to the rear end of the connecting member 17 and have 75 suitably connected thereto strap members for the adjustment of the abdominal supporting sections 19. I prefer to make one 80 of said strap members as 22 of a single piece of material secured to the rear edge of the kidney support 21, while the other strap member 23 is bifurcated as at 24 and 25, and similarly connected to the other of said 85 back supporting members, said strap members 23 terminating in a suitable buckle 24.

As will be clear from Fig. 3, the strap member 22 is preferably passed between the bifurcated members 24 and 25 to the 90 front of the corset, while the member 23 is passed over the back supporting member 21 to the other side of the front of the corset. Hose supporting members as 26 may be secured to the lower edge of the cor- 95 set in the usual manner.

To put on the corset and supporter, the fastenings 20 of the supporter and 13 and 14 of the corset are opened, the laces 12 adjusted to provide the proper width between 100 the corset sections, and the supporter then put on the body by means of the usual horizontal enveloping movement. The abdominal supporter is then approximately adjusted in position by fastening the securing 105 members 20 together, after which the corset may be secured in place by the engagement of the clasp members 13 and 14. After the corset has been put on, it may now become necessary to tighten the abdominal support 110 in order to pull in the abdomen of the wearer to the required position for producing

the slim or slender figure, which is the present highly desired style for women. The adjustment of the abdomen is accomplished by pulling the straps 22 and 23 in opposite directions substantially parallel to the back, whereby the sections 19 are pulled toward the rear and the abdomen thereby pulled in. After the desired pressure on the abdomen has been secured by the above described tension on the straps 22 and 23, said straps may then be brought around to the front of the corset as shown in Fig. 4, and the end of the strap 22 passed through the buckle 24' and secured in adjusted position. The elastic members 11 of the corset will automatically take up the slack which may have been produced in the corset by the tightening of the abdominal supporter 18, so that the wearer is given the slender figure required, while the abdomen is properly supported, though the corset may be further adjusted if desired by means of the laces 12.

It will be noted that not only do the straps 22 and 23 themselves serve to support the figure, but that the back supporting members 21 are pressed close to, and help to support the back of the wearer when the abdominal supporter has been adjusted in place. It will be seen also that the adjustment of the supporter 18 is entirely independent of the adjustment of the corset and that the abdominal supporter and corset are entirely independent devices, functioning separately, excepting that they are maintained against separation from each other merely by the passage through the corset, from the interior to the exterior thereof, of the connecting members 17.

It will further be seen that by reason of the fact that every part of the supporter 18 is movable relatively to the corset 10, perfect adjustment giving any desired equal or unequal pressure on the sides of the body may be obtained. If the pressure on the side of the abdomen is to be varied, the entire supporter may be shifted bodily as required. It will also be seen that the corset may be opened for further adjustment thereof without affecting the adjustment of the abdominal supporter, and that the pressure of the abdominal supporter on the figure may be adjusted without changing the adjustment of the corset. By bringing the straps 22 and 23 around to the front of the wearer it will further be seen that said straps serve as an additional support to the figure, other than that provided by both the corset and the supporter. The corset is entirely unsecured to and free of the supporter at all points, so that both of said members may be moved relatively in any direction to eliminate undue pressure at any particular point on the body. It will finally be seen that while my improved article may be put on at one time the parts may be separately

adjusted, that the adjustment of one of the members may be varied independently of the adjustment of the other member, that proper support is given to the abdomen, to the kidneys and to the entire figure, and that my article is well adapted to meet the hard conditions of practical use.

I claim:

1. In an abdominal supporting corset, a corset member having openings at the sides thereof, upright elastic members in said corset member for maintaining the corset against the body of the wearer, an abdominal supporter inside of said corset member, narrow members passing through said openings and joined to the rear edge of said supporter, said narrow members extending around to the back of the corset, a back supporting member secured to the rear edges of said narrow members and capable of horizontal movement during the adjustment thereof and straps secured to the rear edges of said back supporting members and of sufficient length to be passed around the back, sides and abdomen of the wearer for aiding in the support of the abdomen.

2. The combination with a corset having openings therein, and having upright elastic sections serving as self-constricting means for said corset, of abdominal supporting means arranged inside of said corset, back supporting means arranged outside of said corset, and horizontally adjustable from a point at the sides to a point at the middle of the back of said corset, means passing through said openings connecting said abdominal supporting and said back supporting means, and straps secured to said back supporting means, adapted to be fastened in place independently of said corset and in contact with the back, sides and front of said corset for adjusting the position and the pressure on the body of the wearer of said back supporting and said abdominal supporting means, and for aiding in the support of the back, sides and abdomen of the wearer.

3. A combined abdominal supporter and corset adapted to be arranged in place by an enveloping movement about the body of the wearer comprising a pair of detachably connected abdominal supporting sections, arranged inside of said corset, cooperating members at the front edges of said sections for fastening said sections together, a pair of corset members having openings therein, vertically arranged comparatively narrow elastic sections in said corset, means for detachably securing the front edges of said corset together, connections secured to the rear edges of said abdominal supporting sections passing through said openings to the exterior of said corset members, back supporting sections at the rear ends of said connections, said back supporting sections

being independent of said corset and arranged for substantial horizontal adjustment, and a pair of straps wholly on the outside of said corset and free therefrom, each secured to the rear edge of one of said back supporting members and each of sufficient length to pass across the back of the corset to meet the front of the corset underneath the abdomen, and a buckle on one of said straps for securing said straps together in adjusted position.

4. In combination with a corset having openings at the sides thereof, and open at the front thereof, means for removably fastening the front edges of said corset together, means for relatively adjusting the rear edges of said corset, a pair of separate abdominal supporting sections arranged inside of said corset, quickly detachable and connectable, cooperating fasteners on the front edges of each of said sections, substantially rectangular back supporting members arranged outside of said corset at the back thereof, and adjustable from a point at the sides and extending to the middle of the back of said corset, tapes passing through the side openings of the corset and connecting said back supporting members and said abdominal supporting sections together, and a pair of straps independent of and movable bodily relatively to said corset and each of sufficient length to pass across the back of said corset to the front thereof, for adjusting said back supporting sections, and said abdominal supporting sections, each of said straps being secured to the rear edge of one of said back supporting sections.

EPHRAIM DRENSHTEIN.
